Leslie H. Dubick, 6984 Milbrook Park Drive,
Baltimore, Md. 21215

Continuation of design application Ser. No. 6,366,
Mar. 24, 1967. This application Nov. 21, 1967,
Ser. No. 9,486

Term of patent 14 years

(Cl. D92—11)

The figure is a plan view of a textile fabric showing my new design, the design unit shown above the dot dash line repeats in vertical succession as indicated by the extension below the unit boundary.

This is a continuation of my copending application Ser. No. D. 6,366 filed Mar. 24, 1967, and now abandoned.

I claim:

The ornamental design for a textile fabric, substantially as shown and described.
